UNITED STATES PATENT OFFICE.

ALVIN C. McCORD, OF CHICAGO, ILLINOIS.

DUMPING-CAR.

No. 839,870.

Specification of Letters Patent.

Patented Jan. 1, 1907.

Application filed September 1, 1904. Serial No. 222,912.

To all whom it may concern:

Be it known that I, ALVIN C. McCORD, a citizen of the United States, residing at Chicago, in the county of Cook and State of Illinois, have invented certain new and useful improvements in Dumping-Cars; and I do hereby declare the following to be a full, clear, and exact description of the invention, such as will enable others skilled in the art to which it appertains to make and use the same.

My invention relates to dumping-cars, and has for its object to provide certain improvements in the door-closing devices thereof with a view of securing increased efficiency; and to this end my invention consists of the novel devices and combinations of devices hereinafter described, and defined in the claim.

My invention is illustrated in the accompanying drawings, wherein like notations refer to like parts throughout the several views.

In said drawings, Figure 1 is a view in side elevation, showing a portion of a car equipped with my improvement. Fig. 2 is a cross-section on the line $x^2 x^2$ of Fig. 1, with one of the doors and the locking devices in their closed positions and the other door and locking devices in their open positions, with the door hanging in about the plane it assumes under the action of gravity; and Fig. 3 is a detail on the line $x^3 x^3$ of Fig. 2, showing the locking devices for the hand-lever of the crank-shaft.

The numeral 1 represents the flooring, 2 intermediate sills, and 3 the side sills, of the car-body. To the said side sills are fixed standards or uprights 4, supporting top rails or girders 5, and constituting the side frames of the car. From the top rails or girders 5 are suspended the doors 6 by strap-hinges, the upper members of which are marked with the numeral 7 and are fixed to the rails or girders 5 and the lower or long members of which are marked with the numeral 8 and are fixed to the door-bodies. The hinge members 8 are shown as projecting below the body portions of the doors at the lower ends, these projecting portions being adapted to abut against the flooring 1 and side sills of the car when the door is in its closed position, and thereby limit the inward motion of the door.

To the side sills 3 of the car-body below the floor-level are fixed bearing-brackets 9, in which are mounted shafts 10, having fixed

thereto cranks 11, which are crooked in the planes of their rotation. As shown, the cranks are curved in the planes of their rotation; but the crooks therein might be otherwise formed than on a true curve. The essential thing is that the crooks must be in the plane of the cranks' rotation in order to adapt the cranks to perform the functions intended. Said crank-shafts 10 are provided at the ends thereof adjacent to the ends of the car with hand-levers 12, fixed thereto, which hand-levers 12 have upper end portions adapted to enter between the jaws of bifurcated retaining-clips 13, fixed to the car-frame, and to be held in said clips by keys 14, fitting the enlarged part of the opening between the jaws of the clips, as best shown in Fig. 3, for locking the hand-levers and the crank-shafts in their door-closing positions, as shown in Figs. 1 and 2. Said keys 14 are shown as suspended or, in other words, chained to the car-body.

With this construction a highly-efficient device is secured for closing the car-doors and holding the same in their closed positions against the weight of the load in the car and which device, nevertheless, does not interfere with the opening movement of the doors or the discharge of the load.

The crank-shafts 10 must of necessity be below the level of the lower edge of the doors or any projecting parts thereon in order to afford the necessary clearance for the opening movement of the doors in the dumping action. Likewise the cranks must swing out of the path of the doors in the opening movements of the parts, as the doors must swing outward beyond the outer ends of the cranks. Under these conditions it becomes quite a problem to secure cranks which will engage with the doors under an operative leverage in the closing action and which will afford a strong brace for holding the doors in a closed position against the weight of the load when the crank-shafts are turned inward to their limit. I have solved the problem by providing the crooked cranks 11. It is obvious that with these crooked cranks the shafts 10 may be below the lower edges of the doors or any projections thereon and that, nevertheless, the cranks 11 will swing out of the path of the doors in the opening movements under the limited angular movement or rotation permissible to the shafts, and, further, that in the closing movement the tips of the cranks will engage with the doors under

an operative leverage and that when all the parts are in their closed positions the cranks 11 will afford direct and strong braces between the doors and the shafts 10. It should be especially noted that in virtue of this form of the cranks the strain from the load is all taken in the plane of the cranks' rotation, and hence that the cranks themselves and the shafts 10 are free from any torsional or buckling strain lengthwise of said shaft. It should also be noted that the cranks 11 when in their closed position make the line of strain from the load come so nearly in the line of the dead-centers that in the absence of 15 jolting action the cranks themselves might be relied upon to hold the doors in their closed positions. The hand-levers and locks, however, are desirable to reinforce the cranks and prevent any opening movement thereof 20 under the jars and jolts incidental to the service.

As illustrated, the cranks 11 engage with the downwardly-extended or projecting parts of the hinge-straps 8; but this is not at all 25 essential. On the contrary, it is simply incidental to the presence and use of said projecting parts of the strap-hinges as stops for limiting the inward movement of the car-door. The crooked crank-shafts 11 could 30 be of such length and curvature as to engage with the body portions of the car-doors in the closing action, or, in other words, the projecting parts of the strap-hinges might be entirely dispensed with so far as the action of 35 the crooked cranks 11 is concerned. The lower ends of the straps 8, in one sense, form depending portions of the lower edge of the door.

I am aware that shafts with straight 40 cranks and laterally-extended pins have been proposed and used for closing top-hinged doors of dumping-cars and holding the same in their closed position; but such prior devices have been found in practice to be objectionable, because of the torsional strain 45 on the cranks and the shafts from the load in the car, the tendency being to buckle the cranks and the shafts and to render the same inoperative. Otherwisestated, this old form 50 of locking device did not bring the strain in the plane of the cranks' rotation, and did not

cause the cranks to afford direct braces between the doors and the crank-shafts when the parts were in their closed positions. Moreover, said old forms required projections on 55 the bottoms of the doors or else the notching out of the lower edge of the doors in order to bring the crank-pins into operative relation for closing the doors. The crank-arms 11, it will be seen, are so curved or bent that their 60 intermediate or body portions will never engage with the door. Their rounded free ends, however, are so located that they stand outward of the door in all positions which the door will assume when suspended by gravity. 65 These rounded free ends of said arms engage only with the outer face of the free lower edge of the door. Hence when the cranks are moved inward against the door they exert only an inward pressure thereon, tending 70 to close the same. These difficulties are all overcome in my improvement herein disclosed and claimed.

By actual service I have demonstrated the efficiency of this invention for the purposes 75 had in view.

What I claim, and desire to secure by Letters Patent of the United States, is as follows:

In a dumping-car, the combination with a 80 car-frame and a top-hinged door suspended therefrom, of a door-closing crank-shaft located below said door and outward of the doorway, said crank-shaft having at least 85 one crank-arm that lies in a plane that intersects the axis of said crank-shaft at a right angle, and which crank-arm is so crooked that in all possible positions its intermediate portion will clear the lower edge of the door when the door hangs open under the influence of gravity, and the free end thereof will 90 engage only with the outer surface of the depending free edge of said door, whereby when said crank-arm is moved against the door it will exert only a pressure tending to close the 95 same, substantially as described.

In testimony whereof I affix my signature in presence of two witnesses.

ALVIN C. McCORD.
